UNITED STATES PATENT OFFICE.

ALBERT F. EELLS, OF BOSTON, MASSACHUSETTS.

SUBAQUEOUS FOUNDATION.

No. 895,398.

Specification of Letters Patent.

Patented Aug. 4, 1908.

Application filed November 21, 1907. Serial No. 403,117.

To all whom it may concern:

Be it known that I, ALBERT F. EELLS, a citizen of the United States, residing at Boston, in the county of Suffolk, State of Massachusetts, have invented a certain new and useful Improvement in Subaqueous Foundations With the Tower or Pier Which They May Support, of which the following is a specification, reference being had therein to

10 the accompanying drawing.

My invention relates to the construction of foundations for lighthouses, piers, &c., and is intended to provide means by which such structures can be located at points ordinarily 15 inaccessible and where such structures cannot be built in the ordinary way for the reason of surrounding difficulties, and because the difficulty of transporting material and holding it in readiness for use in the building 20 up of such structures as ordinarily practiced. I have overcome the serious difficulties above enumerated by hereinafter described methods.

The invention pertains more particularly 25 to the construction of masonry to be used under and above water, as piers, towers, etc., and more especially to structures to be placed at sea where by reasons of strong tides, seas, winds, etc., serious delays are caused and 30 oftentimes the partially completed work entirely destroyed and necessarily abandoned.

One of the primary objects of the invention is to provide for the practical completion of the base and a portion of the tower or 35 pier at a port or a point where the material can be readily obtained and easily handled.

After the base is constructed, it is loaded 40 with the material, cement, machinery, stores, framing, etc., for the completion of the structure, the floor of the base having previously been loaded with sufficient broken stone or other material sufficient to weight it and build up the tower to complete the work. The base thus constructed and equipped is 45 then towed to the place where it is to be permanently located. The air previously introduced is then allowed to escape, when the bottom collapses by reason of the weight of the superstructure and the base sinks until it 50 rests upon the bottom of the sea. The divers then enter and remove the frame and collapsed portion of the bottom. The sand is then pumped out from within the base until

the structure sinks to the required depth. After being sunk the sand is returned within 55 the dome which may be entirely filled. The work of completing the tower or whatever superstructure is to be erected upon the base is then proceeded with.

I provide the arched or dome portion of 60 the base with scouring rings extending substantially laterally therefrom for the purpose of preventing the rapid streams of water caused by obstructing the tide from washing away the sand from around the structure. I 65 make the base dome shape of great breadth so as to obtain maximum carrying capacity.

Other objects and advantages of the invention will hereinafter appear and the novel features thereof will be particularly pointed 70 out by the appended claims.

The invention is clearly illustrated in the accompanying drawing which, with the numerals of reference marked thereon, form a part of this specification, and in which is 75 shown a substantially central vertical section through the base and a portion of the tower, being that portion which is built and then floated to its point of destination, where it is afterward sunk to the required depth. 80

In carrying out my invention I construct upon the shore a bottom or platform 1 preferably of wood sufficiently strong to withstand the weight to be borne thereby.

2 is a cutting edge preferably of metal resting upon the outer edge of the platform 1 and surrounding the same. This cutting edge is secured to the bottom or platform 1 by suitable means as the turn buckles 3 whereby the two parts are made fast and tight, suitable packing or gasket being employed if necessary to accomplish this purpose. This platform with its cutting edge is then launched and floated to a position where the completion of the base will be carried on. A 90 suitable framework 6 is then erected upon the said bottom or platform, said framework being suitably braced to give the requisite strength, and then upon the said bottom or platform is placed stone 4 to be used in the 100 completion of the tower after the base reaches its destination. Broken stone in bags as represented at 5 is then placed upon the platform near the center thereof, as shown. A scow or float 16 is then placed upon the 105 platform as indicated. Next an air lock 7

is placed in position centrally, as shown, the said air lock being surmounted by a pump 17 of known construction or of any preferred form. Then a metallic dome 8 is placed in 5 position, being secured rigidly and air tight to the inner wall of the cutting edge 2 and to the flange or base of the air lock 7, as shown. The air pump is then started and pressure increased within the dome as the work progresses, the pressure being proportioned to 10 suit the conditions of construction.

The cutting edge 2 is then filled with concrete or analogous material on which the whole structure will be supported. The 15 structure is then built up of any suitable character, for instance of concrete, as shown at 9, which may be reinforced with metal in any of the well known or approved ways, it being understood of course that broken stone 20 or other material may be employed in connection with the concrete.

10 designates scouring rings built integral with the portion 9, as shown, and 11 designates a surrounding cable disposed beneath 25 these rings to which a towing line 18 may be attached for the purpose of towing the structure to the place where it is to be permanently located.

In completing the base the portion to be 30 permanently located above the water line is formed with water compartments 15, a room above the same, as shown, and a balcony 12 above which the tower may be continued to any desired height, not necessary in this instance to show.

13 is a temporary floor suspended above the dome in any suitable manner and designed to support barrels of cement 14, as shown, and which is designed for the further 40 construction to be carried on. The structure as shown in the drawing is then towed to final position. The air is then allowed to escape, whereupon the full weight of the structure coming upon the cutting edge as 45 the structure sinks causes the bottom to collapse and the water flows in. Then the interior framing and a portion of the collapsed bottom is removed, the stone 4 having been first moved over toward the center for this 50 purpose. Then the sand pumps are started and sand removed from within the area enclosed by the cutting edge, in proximity thereto until the structure sinks to the requisite depth. A portion of the sand is then re- 55 turned within the dome, up around the edges. Then the stone 4 and 5 is removed and hoisted up to complete the tower to the required height, the cement 14 being used in connection with the stone for such purpose. 60 After all of the stone 4 and 5 has been removed, as well as the scow 16, the interior of the dome may be further or completely filled with sand if desired, and up to any desired height above the top of the dome if found de-

sirable. If at any time after the structure is 65 thus sunk, the sea bottom around the structure should shift, the sand may be pumped out and the structure again lowered into proper position, the steps followed being substantially those as above outlined.

Modifications in detail may be resorted to without in any way departing from the spirit of the invention or sacrificing any of its advantages.

What is claimed as new is:-

1. The method hereinbefore described of placing a hollow subaqueous base for piers, lighthouses and like structures, the same consisting in mounting said base, closed at the top, with its lower edge resting upon a temporary bottom, in forcing compressed air into the space within said base and bottom, and in sinking said base in place by releasing the air whereby the bottom is collapsed and the edges of the base sunk to the bottom of 85 the water.

2. The method herein described of building and placing a hollow base for piers, lighthouses and like structures, the same consisting in providing a temporary bottom, in 90 mounting on said bottom a suitably supported dome or shell having its edge resting on said bottom, in building the wall of said base on said dome or shell, in supporting said dome and wall by air forced 95 into the interior, and finally in releasing said air, whereby the bottom is collapsed and the base sunk to the bottom of the water.

3. The method of placing a hollow subaqueous base for piers, lighthouses and like 100 structures, the same consisting in permitting compressed air in the space within said base to escape and effect collapse of its bottom to allow the base to sink to the bottom of the water, and then filling the space within the 105 base with sand or analogous loose material to give stability to the structure.

4. A subaqueous base for piers, lighthouses and like structures comprising a hollow wall built upon a temporary bottom, 110 said wall and bottom inclosing hermetically the space, substantially as described.

5. A subaqueous base for piers, lighthouses and like structures comprising a wall built upon a suitably supported metallic 115 shell and a temporary bottom on which the base rests, substantially as described.

6. The method of floating a subaqueous arched foundation which consists in closing the same underneath overcoming the upward pressure of the water against its bottom by bracing said bottom against said upward pressure.

7. The method of floating a subaqueous foundation which consists in closing the same 125 underneath overcoming the upward pressure of the water against its bottom by the application of weight above said bottom.

8. The method of floating a subaqueous foundation which consists in closing the same underneath the application of weight and air above the bottom to overcome the upward pressure of the water against said bottom.
9. The method of floating a subaqueous foundation which consists in closing the same underneath overcoming the upward pressure of the water against the bottom thereof, by
- the combined influence of air, weight and a suitable bracing.
10. A subaqueous foundation provided with a scouring ring.
